UNITED STATES PATENT OFFICE.

GEORGE RUSSELL KENNEDY, OF PITTSBURGH, PENNSYLVANIA, ASSIGNEE OF ONE-HALF TO GRANT McCARGO, OF PITTSBURGH, PENNSYLVANIA.

LUBRICATOR.

1,071,754.

Specification of Letters Patent.

Patented Sept. 2, 1913.

Application filed April 18, 1911. Serial No. 621,898.

To all whom it may concern:

Be it known that I, GEORGE RUSSELL KENNEDY, a resident of Pittsburgh, in the county of Allegheny and State of Pennsylvania, have invented a new and useful Improvement in Lubricators, of which the following is a specification.

This invention relates to lubricators and more particularly to feed cups for lubricants in which pressure is employed to cause the flow or movement of the lubricant out of the cup.

The present invention is an improvement upon the lubricator shown, described and claimed in my Patent No. 906,720 granted December 15, 1908.

The object of the present improvement is to simplify the construction of the lubricator covered by my former patent, to render the same cheaper to manufacture, and generally to improve the construction and operation thereof.

The invention comprises the construction and arrangement of parts hereinafter described and claimed.

In the accompanying drawings Figure 1 is a vertical sectional view through one form of the improved lubricator; Fig. 2 is a detail view of the piston or plunger and the escapement mechanism showing the escapement mechanism locked; Fig. 3 is a similar view showing the escapement mechanism released; Fig. 4 is a detail sectional view showing the nut in the head or cap of the cup; Fig. 5 is a plan view of the same; Fig. 6 is a vertical sectional view through a modified form of the lubricator; Fig. 7 is a detail view of a follower member; Fig. 8 is a detail view of the spring shown in Fig. 6; Fig. 9 is a detail view of one of the springs shown in Fig. 1, and Fig. 10 is a sectional view of a modified form of the invention in which the piston has been raised to its upper position.

The cup 1 is preferably cylindrical as is customary and is provided with a removable lower head 2 threaded onto the body as shown in Fig. 1. If desired the head or cap 3 of the cup may also be detachably attached to the body as described in my former patent above identified. The cup may be filled with lubricant either by removing the lower head 2, or in any other suitable way, depending upon the character of the lubricant, as fully described in my prior

patent. The lower head 2 of the cup is provided with a threaded discharge nozzle 4 as is customary, for attachment to the bearing or part to be lubricated. The discharge opening 5 through this nozzle is made large enough for the maximum discharge of lubricant desired, and is controlled by suitable means for restricting the discharge, the controlling means shown being a threaded plug 6 arranged transversely of the discharge opening and provided with a transverse port 7. By rotating this plug the size of the discharge opening can be reduced to any desired extent, as will be readily understood. Formed in, or suitably secured non-rotatably to the body or cap 3 of the cup is a nut 8, provided with a thread or threads 9 of quick pitch, there preferably being a pair of such threads. Extending through the nut is the threaded rod or shaft 10 which is provided with spiral grooves 11 of quick pitch co-operating with the threads 9 in the nut 8. The threads on the rod or shaft and in the nut, are of such quick pitch that when force is applied to the shaft in the direction of its length said shaft is caused to rotate in the nut. Preferably the threads are double as shown, in order to support the rod or shaft 10 at diametrically opposite sides, and thereby keep the same more accurately in vertical position. Within the cup is a piston or plunger 12, shown provided with a cup leather, although if desired it may be of solid construction. This piston or plunger has a sliding fit in the cup and is adapted to be shifted lengthwise therin by suitable controlled means as hereinafter described. As shown it is rotatably and slidably mounted on a central stud or rod 14 formed on or secured to the lower end of the threaded rod or shaft 10, the specific construction shown having the stud 14 projecting into an axial hole in the threaded rod or shaft 10 and secured therein by cross pin 15. At its lower end the stud 14 is provided with a washer 16 and cross pin 17 to limit the longitudinal movement of the piston or plunger thereon and prevent disengagement lengthwise of these parts, and also to disengage the ratchet 18 when raising the plunger for filling. The piston or plunger is controlled by substantially the same means as in my patent above identified, that is to say by means of the shifting or feeding spring 20 and the pres-

sure spring 21. Both of these springs are of spiral conical formation. The spring 20 serves to shift or feed downwardly the threaded rod or shaft 10, and to maintain substantially constant the tension of the spring 21 which serves as the effective means for maintaining pressure on the lubricant in the cup, and which by reason of the feeding or shifting spring 20 and escapement mechanism hereinafter described exerts an approximately uniform pressure upon the lubricant irrespective of whether the cup is filled or nearly empty. As shown, the spring 20 is interposed between the cap 3 of the cup and the follower member or washer 23 which loosely surrounds the lower end of the threaded rod or shaft 10; while the spring 21 is interposed between this same follower or washer 23 and the piston or plunger 12, as shown.

Interposed between the piston or plunger 12 and the threaded rod or shaft 10 is suitable escapement mechanism to control the shifting or feeding action of spring 20. This escapement mechanism comprises a crown piece or ratchet member 24 which is non-rotatably and lengthwise immovably secured to the threaded rod or shaft 10 such as by means of the cross pin 15, and which is provided with an annular series of ratchet teeth 25, which are engaged by a pawl member or tooth 26 formed on or suitably secured to the piston or plunger 12. Interposed between the crown wheel 24 and the follower or washer 23 is a suitable ball bearing 27. The shifting spring 20 holds the follower or washer 23 constantly pressed against the ball bearing 27 and as the latter is supported by the escapement wheel 24 which is secured to the threaded rod or shaft 10, it is apparent that the shifting spring 20 exerts endwise force on the threaded rod or shaft 10, so that it will cause endwise movement and resultant rotation of the threaded shaft or rod 10, whenever the escapement mechanism is released. This is effected as follows: When the piston or plunger 12 is exerting pressure upon the lubricant in the cup the escapement members are held interlocked, or in the position shown in Figs. 1 and 2. The pressure of the springs in one direction and of the lubricant in the opposite direction exerts sufficient force on the piston or plunger to prevent its rotation under the propelling action of the springs. Consequently the ratchet tooth 26 is relatively stationary, that is non-rotatable and serves to lock the ratchet wheel 24 against rotation. As a consequence the threaded rod or shaft 10 cannot rotate in the nut 8 and is for the time being endwise immovable. As the lubricant slowly flows out of the cup the spring 21 gradually expands, forcing the piston or plunger 12 downwardly as fast as

permitted by the escape of the lubricant, until the ratchet tooth 26 is drawn out of engagement with the escapement wheel 24, or to the position shown in Fig. 3. The threaded rod or shaft 10 is now free to rotate, and does so by reason of the force exerted endwise thereon by the shifting spring 20, thereby shifting the rod 10 downwardly until the escapement 25 again engages the tooth 26. This has the effect of again compressing the spring 21, and the parts again remain in this position with the piston being gradually forced downwardly by spring 21 as fast as allowed by the escape of the lubricant, until the escapement mechanism is again released. The result is that the bearing or abutment for the pressure spring 21, represented by the washer 23, is intermittently shifted downwardly, so as to maintain the spring 21 under substantially constant tension and irrespective of whether the cup is full or nearly empty, and insuring a constant feed of the lubricant from the cup. Obviously the spring 20 must be stronger than the spring 21.

The piston or plunger 12 can be raised, to fill the cup or for other purposes, in two ways. As shown in Fig. 1 the threaded rod or shaft 10 has secured to its upper end a suitable handle 28 which can be grasped and by means of which said threaded rod or shaft can be turned in the proper direction, whereby the interengaging threads 9-11 cause said threaded rod to move endwise and lift the plunger. The threaded rod or shaft 10 is also provided with another set of threads 30 of slow pitch and which are engaged by a nut 31 of similar pitch. This nut during the normal operation of the feed cup lies underneath the handle 32 near the upper end of the threaded rod, so that it does not interfere with the downward shifting of said threaded rod as above described. When the plunger is raised by rotating the screw 10 as above described, the nut 31 can be run down until it presses against the top of the cup body and will then prevent downward movement of the threaded rod or shaft 10 until the cup is filled. As soon as the cup is filled this screw is again run up until it lies below the handle 28, so that it will not interfere with the downward movement of the screw as heretofore described. The nut 31 can also be used for lifting the threaded rod or shaft 10, and this is the intention in the modification shown in Fig. 6, in which the threaded rod at its upper end is merely provided with a head or slight enlargement 32a. To lift the plunger the nut 31 while in contact with the top of the cup, is turned in the proper direction, and by reason of its engagement with the slow pitch threads on said threaded rod or shaft, the latter is gradually lifted, also turning as it is being lifted, on account of the quick pitch threads 9-11. 130

The turning of the nut is continued until the piston or plunger is lifted to the proper extent, and said nut then holds said piston or plunger elevated while filling the cup. As soon as the cup is filled the nut is run to the upper end of the threaded rod as above described. If it is desired to stop the lubrication it is merely necessary to run the nut 31 down until it contacts with the top or cap 10 of the cup, when it will prevent the downward shifting of the piston, as will be readily understood.

In Fig. 10 I have illustrated a construction in which the slow pitch threads 30, shown in Fig. 1, have been omitted. In this form of the invention the rod or shaft 10^a has a smooth exterior surface except for the grooves 11, of quick pitch, which engage with the teeth 9 on the central or nut portion 8^a of the head or cap 3, in the same manner as in Fig. 1. At its upper end the rod or shaft 10^a is provided with a handle 32, non-rotatably secured thereto, and at its lower end is formed an annular groove or depression 36 of slightly greater width or extent along the shaft than the thickness of the head or cap 3 at this point. The quick pitch threads in this form merge directly into the annular groove 36. With the arrangement described, the piston and shaft are moved upwardly for filling the cap by a direct hand pull exerted on the handle 32, a slight turning motion being given at the same time to cause the grooves 11 to ride 35 along the projections or teeth 9. When the piston and shaft have reached the upper limit of movement, a further quarter turn of the handle 32 and shaft 10^a will cause the upper side edge of the annular groove 40 36 to ride around on the face 8^a of the cap 3 and hold the shaft and piston from downward movement. This construction offers a quick and convenient means for filling the lubricator and dispensing entirely with the 45 nut 31 and screw threads 30 of Fig. 1. At the same time it will be obvious that I may apply the annular groove 36 to the other forms of my lubricator shown in the drawings and I intend to so use it. For example, 50 by applying the annular groove 36 to the form shown in Fig. 1, the piston there shown may be quickly retracted by direct hand pull, as in Fig. 10, and held in position by quarter rotation of the shaft or it may be 55 slowly raised by operation of the nut 31 in the ordinary manner.

The springs 20 and 21 may if desired be formed as a single continuous hour-glass spring, and is so shown in Figs. 6 and 8, 60 where the two parts of the spring are marked respectively 20^a and 21^a. With this modification the washer or follower 23 will be so formed as to allow the continuous spring to pass therethrough, such as being 65 provided with an opening 35. This single

spring to all intents and purposes acts in exactly the same way as the two springs shown in Fig. 1, the upper portion 20^a acting as the shifting or feeding spring and the lower portion 21^a serving as the pressure 70 applying spring.

The springs 20 and 21 are preferably formed of wire which gradually tapers, the heavier section of wire forming the larger turns or bases of the springs, and the 75 lighter section forming the smaller turns or apexes of the springs. Fig. 9 illustrates this in a somewhat exaggerated form, as in actual practice the taper in the wire from the base to the apex is only very slight. 80 This provides a conical spring of uniform tension in all of its turns, it being obvious that the smaller the turn the lighter the wire can be to secure a given pressure or force. Fig. 9 shows this principle applied to the 85 feeding or shifting spring 20, but it is also applied to the pressure spring 21. This principle is also applied to the double spring shown in Figs. 6 and 8, and Fig. 8 illustrates the tapering of the wire from both 90 ends of the spring toward its intermediate contracted portion, the amount of taper being exaggerated to make it apparent.

The lubricator described comprises the same general principles as that of my prior 95 patent hereinbefore identified, and serves to maintain an approximately uniform pressure on the lubricant in the cup at all times, and irrespective of whether the cup is full or nearly empty. The mechanism however is much simpler than in my prior patent, and the cup is cheaper to manufacture and less liable to derangement. Furthermore, the complicated ratchet or escapement mechanism of my former patent, which was on the exterior, is replaced by simple escapement mechanism located within the cup and therefore less liable to injury. The grooved or splined condition of the threaded rod or shaft which was a necessary feature 100 on my former patent is entirely obviated, and in place of the duplicate crown ratchet wheels of my former patent, one wheel and one tooth or pawl are used, and simpler and more effective means are provided for lifting the piston and threaded rod. In the improved arrangement also the conical spiral springs are not attached at either end, but merely rest at either end upon the bearing members, thereby not only cheapening 110 the manufacture but making the device simpler to assemble and take apart.

What I claim is:

1. In a lubricator, the combination of a cup, a piston or plunger within said cup, a solid externally threaded rod or shaft having an endwise projecting stud for supporting the piston, a spring interposed between said threaded rod and piston for moving the latter with reference to the rod, a nut fixedly 125

- connected to the cup and engaging said threaded rod, a spring interposed between the cup and the threaded rod and arranged to move the same longitudinally and there-
6 by rotate the same in said nut, and a nut eng-
gaging the threads on said rod outside of
said cup.
2. In a lubricator, the combination of a cup, a piston or plunger, a solid externally
10 threaded rod or shaft having a projecting stud at one end thereof, a piston rotatable on said stud, a collar on said stud to confine the piston thereon, a spring interposed be-
tween the threaded rod and piston, a nut
15 fixedly connected to the cup and engaging said threaded rod, a spring interposed be-
tween the cup and the rod and serving to move the latter longitudinally and rotate the same in said nut, escapement mechanism
20 connecting the piston and rod and arranged to control the action of the last named spring, and a nut on said threaded rod outside of said cup and adapted to contact the same and limit the motion of said rod.
- 25 3. In a lubricator, the combination of a cup, a solid rod or shaft extending through the top thereof and interengaging the same by quick pitch threads, a piston or plunger rotatably and longitudinally movable on said rod or shaft, a feeding spring arranged to constantly exert endwise force on said rod or shaft, a pressure spring between the piston and a part moving with the rod or shaft under the action of the feeding spring,
30 escapement mechanism between said rod or shaft and the piston for controlling the action of the feeding spring, said mechanism comprising an annular toothed member non-rotatably connected to said shaft, and a
35 single interlocking tooth or pawl carried by said piston and adapted to coöperate with said annular toothed member.
4. In a lubricator, the combination of a cup, a threaded rod or shaft extending
45 through the top thereof and interengaging the same by quick pitch threads, a piston or plunger rotatably and longitudinally movable on said rod or shaft, a feeding or shifting spring arranged to constantly exert
50 endwise force on said rod or shaft, a pressure spring between the piston and a part moving with the rod or shaft under the action of the shifting spring, escapement mechanism between said rod or shaft and
55 the piston and comprising an annular toothed member and an interengaging tooth or pawl, said rod or shaft being also provided with slow pitch threads, and a nut thereon provided with corresponding slow
60 pitch threads.
5. In a lubricator, the combination of a cup, a piston or plunger therein, a rod or shaft, a spring interposed between said rod or shaft and the piston, a nut engaging said
65 rod or shaft by quick pitch threads and be-
ing non-rotatably supported on the cup, a spring interposed between the cup and said rod and serving to move the latter longitudinally and rotate the same in said nut, said rod or shaft also being provided with a set 70 of slow pitch threads, and a nut engaging said rod outside of the cup by corresponding slow pitch threads.
6. In a lubricator, the combination of a cup, a piston or plunger therein, a rod or shaft, a spring interposed between said rod or shaft and the piston, a nut engaging said rod or shaft by quick pitch threads and being non-rotatably supported on the cup, a spring interposed between the cup and said rod and serving to move the latter longitudinally and rotate the same in said nut, said rod or shaft also being provided with slow pitch threads, a nut engaging said rod outside of the cup by corresponding slow pitch threads, and escapement mechanism controlling the second named spring.
7. In a lubricator, the combination of a cup, a piston or plunger therein, a rod or shaft, a spring interposed between said rod and piston, a nut engaging the rod or shaft, and non-rotatably supported on the cup, said rod and nut being provided with interengaging quick pitch threads, a spring inter-
80 posed between the cup and the threaded rod and acting to move the latter longitudinally and rotate the same in said nut, said piston being rotatably and endwise movable relative to said rod, escapement mechanism between said threaded rod and piston and comprising an annular toothed member secured to one of said parts and an escapement tooth or member secured to the other of said parts, said rod or shaft being also provided with slow pitch threads, and a nut 85 engaging said rod outside of the cup by co-
operating slow pitch threads.
8. In a lubricator, the combination of a cup, a plunger, a pressure spring for shifting the plunger along the cup, and a spring 90 for maintaining the tension of the pressure spring constant, said springs together being of hour-glass form and formed of a single wire of decreasing cross section from the larger end turns of the springs to the smaller 95 middle turns thereof.
9. In a lubricator, the combination of a cup, a plunger, a spring member for shifting the plunger along the cup, and another spring member for maintaining the tension 100 of said spring constant, both of said spring members being coiled from a continuous wire, and a bearing member interposed between the two springs and provided with an opening through which the connecting part 105 of the spring passes.
10. In a lubricator, the combination of a cup, a plunger, a threaded shaft, a spring member interposed between the shaft and plunger, a nut engaging the shaft, and a 110

spring member for rotating one of said parts, both of said spring members being coiled from a continuous wire, and a bearing member interposed between the two 5 springs and provided with an opening through which the connecting part of the spring passes.

In testimony whereof, I have hereunto set my hand.

GEORGE RUSSELL KENNEDY.
